(57) **CLAIM**

The ornamental design for a display screen with icon, as shown and described.

DESCRIPTION

FIG. 1 is a front view of a display screen with icon showing my new design, but shown enlarged and separate for clarity of illustration; and,

FIG. 2. Is a perspective view of the display screen with icon. The broken lines in FIG. 2 show an outline of a remote control device screen and form no part of the claimed design.
